[57] CLAIM

The ornamental design for a bulging ring band, as shown and described.

DESCRIPTION

FIG. 1 is a top perspective view of a bulging ring band showing my new design;

FIG. 2 is a side elevational view thereof, all sides appearing the same; and,

FIG. 3 is a top plan view thereof, the bottom view being the same as the top.

The article shown in broken lines is for illustrative purposes only and forms no part of the claimed design.
